(57) **CLAIM**

The ornamental design for a trolley for handling goods, as shown and described.

DESCRIPTION

1.1 is a front view of a trolley for handling goods;

1.2 is a left side view thereof;

1.3 is a right side view thereof;

1.4 is a rear view thereof;

1.5 is a top view thereof;

1.6 is a bottom view thereof; and

1.7 is a front perspective view thereof.

The broken lines depict portions of the trolley for handling goods that form no part of the claimed design.
